UNITED STATES PATENT OFFICE.

HARRY WINTER, OF SPRINGFIELD, ILLINOIS.

MEANS FOR FORMING SIDE-CUT BRICK.

Application filed November 3, 1921. Serial No. 512,549.

To all whom it may concern:

Be it known that I, HARRY WINTER, a citizen of the United States, residing at Springfield, in the county of Sangamon and State 5 of Illinois, have invented a new and useful Means for Forming Side-Cut Brick, of which the following is a specification.

The invention relates particularly to wire-cut brick of the type known as side-cut brick, which are produced from a continuously moving column of clay. Prime purposes of the invention are: to produce, at 10 one operation, without repressing, side-cut brick having rounded longitudinal edges; and to produce, at the same operation, useful or ornamental configurations on one face 15 of the brick, as will be hereinafter described.

Other purposes of the invention are: to 20 provide in conjunction with means for forming and propelling the clay column, and in conjunction with wires for cutting side-cut brick from the clay column, formers adapted to form the longitudinal edges of the brick 25 contemporaneously with the cutting of the brick; to provide formers adapted to configure one face of each brick contemporaneously with the cutting of the brick; and to provide improved details of construction.

With these ends in view my invention consists of the brick, as an article of manufacture, and in the new and useful means for producing the brick without repressing, all of which will now be fully described and 35 will be finally recited in the claims.

The invention is illustrated in the annexed drawings to which reference is hereby made, in which:

Figure 1 is a side elevation of a brick 40 made in accordance with my invention.

Fig. 2 is a top plan of the same brick.

Fig. 3 is a vertical section through the brick on the line 3. 3. of Fig. 2.

Fig. 4 is an elevation of a fragment of a 45 wall, showing the brick laid in the wall.

Fig. 5 is a side elevation of a machine of preferred construction, usable for cutting and forming the brick. In this view I have shown only such parts of the brick-machine 50 as are necessary to illustrate the cutter mechanism and its mode of operation.

Fig. 6 is a top plan of the same machine.

Fig. 7 is an end view of the cutter mechanism of the same machine.

Fig. 8 is an enlarged vertical transverse

section through the same machine on the line 8. 8. of Fig. 5.

Fig. 9 is an enlarged top plan of a fragment of the upper platen.

Fig. 10 is a vertical transverse section through the upper platen on the line 10. 10. of Fig. 9.

Fig. 11 is an enlarged vertical section through three members of the upper platen, 65 taken on the line 11. 11. of Fig. 8.

Fig. 12 is a plan view of one clearance or former plate.

The same reference numerals designate 70 the same parts in all the views.

Experience shows that the roughness of the sides of wire cut brick is advantageous, especially when the brick are used for street paving, because the cement or other filler used in the joints sets more firmly on and 75 more securely holds the brick than is possible with smoother surfaced brick. In practice it has been found that the longitudinal edges of wire cut brick are thin and sharp and likely to injure the hands of persons handling them, and furthermore are likely to be chipped or broken during the testing of the brick, which is usually done by placing a number of brick in a rattler and rotating it to tumble the brick in contact with each 80 other, often resulting in considerable loss by reason of chipping or breaking of the brick. To overcome these objections, the practice, prior to my invention, has been to repress the brick, but the operation of repressing necessitates a costly handling of 85 the brick and furthermore tends to laminate and injure the texture of the brick, so that for some purposes, especially street paving, the repressed brick is not as strong and dependable as side-cut brick which have not 90 been repressed. In view of the conditions stated, I have devised and produced wire cut brick having the advantageous rough sides and rounded and smoothed edges, and have 95 accomplished this result without disturbing or impairing the original texture of the brick and without the costly rehandling and repressing.

The mechanism employed to produce this 105 result will now be described.

The numeral 12 designates the main frame of the brick machine. A first shaft 13 is rotative in suitable bearings on the main frame. A broad-face gear 15 is loose on the 110 shaft. Automatically acting clutch members 14 co-act with the gear 15 to cause it to make

one complete revolution with the shaft at predetermined periodic intervals, and then stop, and then make another periodic revolution, and again stop, and so on; the rotation of the gear being timed to accord with the forward travel of the clay-column and the simultaneous rearward travel of the carriage, in a manner which is well known in the art. A carriage 16 is adapted to slide 10 on the main frame in the direction of its length. A second shaft 17 is rotative in bearings 18 on the carriage. A cog gear 19 fixed on the shaft 17 meshes with and is driven by the broadface gear 15. The diameter of the driven gear 19 is twice the diameter of the driving gear 15, hence each complete revolution of the driving gear will cause a half revolution of the driven gear. Arched yokes 20 are secured on an oscillative 15 shaft 21 supported by hangers 22 on the carriage. Crank plates 23 are fixed on the shaft 17. Connecting rods 24 connect the crank plates with yokes 20 in such manner that rotation of the cranks will produce 20 intermittent oscillations of the yokes according to the intermittent rotation of the drive gear 15.

The clay-column 25 is formed by dies which are part of the brick machine proper 30 and is forwarded continuously by means well known in the art, which need not be described here. Cross bars 26 connect the yokes so that the yokes move in unison.

A series of taut cutting wires 27 connected 35 with the cross bars 26 and suitably spaced apart from each other cut transversely through the clay column at each to or fro movement of the yokes, the cuts being made alternately from the respective sides of the 40 clay column.

In order that the cuts may be made alternately from opposite sides of the clay column it is necessary that the carriage be clamped on and travel in perfect unison with 45 the clay column while the cuts are being made, and that when the cut from one side is completed the carriage shall be released from the clay column to permit it to advance independently of the carriage and the carriage to be retracted independently of the clay column, to such extent that when the carriage is again clamped on the clay column, the carriage and the clay column will be in such relation to each other that the 50 next cut may be made from the opposite side of the clay column without any considerable waste of clay.

The clay column slides on the stationary lower plates 28. The upper platen 29 is 60 parallel to the lower platen and movable vertically relative thereto.

The means for effecting vertical movement of the upper platen relative to the clay column 25 and the lower platen 28 will now be 65 described. Standards 31 are stationary on

the carriage 16. Arms 32 are connected with the respective standard 31 by pivots 35. On each yoke 20 are two oppositely inclined cams 34 suitably spaced apart from each other and adapted to engage on rollers 33 70 at the upper ends of the respective arms 32. At each end of the carriage is a pair of stationary vertical rods 36. Cross heads 37, one at each end of the carriage, have integral tubular members 38 adapted to slide on the 75 rods 36. Springs 39 surround the rods 37 and act to pull the cross heads upward. The arms 32 are connected with the respective cross heads by pivots 51. Each half-revolution of the crank plates 23 will operate the 80 connecting rods 24 to swing the yokes 20 to the right or to the left, as the case may be. Starting with the parts in the position relative to each other, shown in Fig. 7, the first swing of the yokes will cause the wires 27 85 to cut from right to left through the clay bar 25, and the second or reverse swing of the yokes will cause the same wires to cut from left to right through the clay column; and in like manner alternating right and left cuts 90 will be made so long as the machine continues in operation. In Fig. 7 the yoke 20 is shown at the limit of its right-hand oscillation, the left hand cam 34 is under the roller 33, the cross head 37 and the upper 95 platen connected therewith are raised to permit the clay column to slide freely under the upper platen and the springs 39 are compressed. If the yokes be started to swing to the left, the first effect will be to withdraw 100 the cam 34 from under the roller 33, and thereupon the springs 39 will act to push downward the yokes 37 and the upper platen connected therewith, to cause the upper platen to engage the clay column so firmly 105 that the carriage will travel with the clay column; and the continued swing of the yokes to the left while the carriage is traveling in unison with the clay column, will cause the wires to cut off a number of bricks 110 according to the number of wires that are used. Immediately upon completion of the right to left cut, the right hand cams 34 will engage the rollers 33 to effect the raising of the yokes 37 and the upper platen connected 115 therewith, and hold them in readiness for the next cut. In order that successive cuts may be made as rapidly as is consistent with the regular continuous advance of the clay column, without waiting for the clay column 120 to travel the full length of the carriage, means are provided for sliding the carriage rearwardly simultaneously with forward movement of the clay column. The forward movement of the carriage is a result of the 125 engagement of the depressed upper platen with the forwardly moving clay column. Timely reverse or backward movement of the carriage is effected by a reciprocable rod 50 connected with one end of the carriage 130

and actuated and timed by suitable means which are not part of the present invention and therefore need not be described. During both the forward and the rearward travel 5 of the carriage the gear 19 slides in mesh with gear 15 and is effective to operate the yokes at just the right instant, according to the speed of travel of the clay column.

Each of the platens 28 and 29 comprises 10 a series of units separated from each other by the slots 30. The units are all alike, so a description of one will suffice for all. Each unit comprises a block-like member 40, having internally screw-threaded bores 41; 15 a basal or attaching plate 42; bolts 43 connecting the plate 42 with the member 40; fillet or former bars 44; screws 45, connecting the bars 44 with the plate 42; a clearance or former plate 46, movable vertically be- 20 tween the bars 44; adjusting screws 47 screwing into the plate 46, and adapted to slide in the bores 41; springs 48 surrounding the adjusting screws between the plates 42 and 46; stub screws 49 screwing into the re- 25 spective bores 41; and jam-nuts 50 engaging on the screws 49. The bars 44 have integral former members 53 adapted to form and compress the longitudinal edges of the brick adjacent to the slots 30. The external face 30 of the intermediate plates 46 is normally in the same horizontal plane with the edges of the members 53 and occupies the space between the bars 44 so that the upper and lower surfaces of the clay column will not 35 be scraped or injured by the members 53 during the travel of the clay column between the platens. The lower faces of the plates 46 of the upper platen are preferably, but not necessarily, provided with intaglio configura- 40 tions 54 adapted to produce corresponding relief configurations 55 on one face of the brick. The springs 48 are calibrated to normally keep the external faces of the plate 46 in the plane of the edges of the 45 members 53, but must yield, while the upper platen is being depressed in order to permit the members 53 to be pressed into the clay column and to permit the plates 46 to form the configurations on the upper surface of the 50 brick. When the members 53 are pressed into the clay column they keep it from wobbling or slipping and guide the cutting wires, thus assuring straight cutting of the brick; they also form smoothly pressed lon- 55 gitudinal edges on the brick. The smoothly pressed edges of the green brick facilitate handling in taking the brick from the belt and are less subject to finger prints or mar- ring than are the soft, thin edges of ordi- 60 nary wire cut brick.

During the downward movement of the upper platen the plate 46 will bear on the upper face of the clay column while the bars 44 are moving downward; it is necessary however, in order to form smooth

brick, that the downward movement of the bars relative to the plate shall cease at the instant that the plane of the under surface of the bars coincides with the plane of the under surface of the plate. This result is 70 attained by screwing the stub screws 49 into the bores 41 to such depth that when the platen descends until the plane of the lower surfaces of the bar 44 coincides with the plane of the lower surface of the plate 46 75 the heads of the screws 47 will stop against the inner ends of the stub screws and prevent further movement of the parts 44 and 46 relative to each other, during continued descent of the platen. When the parts have 80 been adjusted as described the jam nuts 50 will be screwed down to secure the stub screws 49.

The characteristics of the brick and the operation of the machine will be easily understood upon reference to the drawings and the foregoing description.

I do not restrict my claims to the precise details of construction herein set forth, inasmuch as it is obvious that minor details 90 may be varied and still keep within the legitimate scope of my invention.

Having fully described my invention, what I claim as new and desire to secure by Letters Patent is:

1. In a machine for cutting and forming side-cut brick at one operation, a platen consisting of a plurality of units spaced apart from each other, each unit comprising edge formers adjacent to and parallel to edges 100 of the unit.

2. In a machine for cutting and forming side-cut brick at one operation, a platen consisting of a plurality of units spaced apart from each other, each unit comprising edge 105 formers adjacent and parallel to edges of the unit; and a face former intermediate of the edge formers.

3. In an apparatus for simultaneously side-cutting brick and forming the longitudinal edges thereof; the combination of a moving platen having transverse slits; taut cutting devices traversing the slits of the platen; and formers on the platen and adjacent and parallel to the slits of the platen. 110

4. In an apparatus for simultaneously side-cutting brick, forming the longitudinal edges of the brick and forming one face of the brick; the combination of a movable platen having transverse slits; taut cutting 120 devices traversing the slits of the platen; edge formers fixed on the platen and adjacent and parallel to the slits thereof; and face formers intermediate of the edge formers.

5. In an apparatus for simultaneously cutting and forming side-cut brick, the combination of a moving platen having transverse slits; a cutting device comprising taut wires traversing the slits of the platen, edge- 125

formers fixed on the platen adjacent and parallel to the slits thereof, and a spring pressed former intermediate of said edge-formers.

5 6. In an apparatus for cutting side-cut brick from a continuously moving clay column and forming the brick coincidently with the cutting; the combination of a platen associated with the forwardly moving 10 clay column; taut cutting wires effective to cut right and left through the moving clay column; edge-formers, one on each side of each cutting wire; and automatic means for dissociating the platen from the clay 15 column.

7. In an apparatus for cutting side-cut brick from a continuously moving clay column and forming the brick coincidently with the cutting; the combination of a platen 20 associated with the moving clay column; edge formers and face-formers on the platen; and automatic means for dissociating the platen from the clay column.

8. In an apparatus for cutting side-cut brick from a continuously moving clay column and forming the brick coincidently 25 with the cutting; a platen automatically associative with and automatically dissociable from the clay column; cutting devices adapted to cut side-cut brick from the clay column; and edge formers and face-formers conjoined with the platen.

9. In an apparatus of the class described, the platen structure comprising a plurality 30 of members separated by slits, each member having a plurality of bores; basal plates detachably connected with the respective platen-members; a pair of fillet bars attached to each basal plate; clearance plates 35 movable between each pair of fillet bars;

adjusting screws slidable in the respective bores of the platen-members and screwing into the clearance plates; springs acting to slide the clearance plates outwardly; and means for limiting the movement of the adjusting screws in the bores of the platen-members.

10. In an apparatus for cutting side-cut brick from a continuously moving clay-column and forming the longitudinal edges 50 of the brick co-incidently with the cutting of the brick, consisting of a carriage; automatic means for periodically associating the carriage with the clay column to travel in unison therewith; automatic means to periodically release the carriage from the clay-column and cause it to travel reversely to the direction of travel of the clay-column; yokes pivoted on the carriage and oscillative transversely relative to the clay-column; taut 55 wires connected with the yokes and effective to cut transversely, both right and left, through the clay column; a movable platen having transverse slits accommodating the cutting wires; means for moving the platen 60 to contact with the clay column previous to each cutting and keep it in contact therewith during that cutting; and formers on the platen, parallel to the slits thereof, and adapted to form the longitudinal edges of 65 the brick during each operation of the platen.

In witness whereof I have hereunto signed my name at Springfield, Illinois, this 13th day of April, A. D. 1920.

HARRY WINTER.
